FRANK A. HURLBUT, OF KANSAS CITY, MISSOURI.

WATER-BACK CONSTRUCTION FOR FURNACES.

1,269,083.

Specification of Letters Patent. Patented June 11, 1918.

Application filed June 24, 1916. Serial No. 105,725.

To all whom it may concern:

Be it known that I, FRANK A. HURLBUT, a citizen of the United States, residing at Kansas City, in the county of Jackson, State 5 of Missouri, have invented certain new and useful Improvements in Water-Back Constructions for Furnaces, of which the following is a full and exact specification.

The present invention relates to improvements in furnaces, with particular reference to boiler furnaces, and aims to devise an improved construction of water back or water circulating member at the bridge wall end of the fire chamber. To this end, a water 10 circulating member is provided in the required position, and in this connection it is an object of the invention to further increase the life or durability of this water back member by a novel arrangement and construction of the same whereby a more rapid water flow is produced past those portions of the member which are subjected to the strongest heat influence, so that the efficiency of the member as regards transfer 15 of heat is likewise promoted.

It is also an object to provide such a construction that the quickening of the water flow at the required points will enable a smaller quantity of water or equivalent fluid 20 to be used as a circulating medium, and without materially decreasing the volumetric capacity of the member itself.

For carrying out the purposes of the invention, a construction has been devised in 25 which the fluid containing casing is provided with means for causing the flow therethrough to follow principally a course along the walls which are chiefly exposed to the direct action of the heat, and it may be 30 pointed out that the novel features in this relation may find other analogous uses not specially dwelt upon or emphasized in this specification.

With the foregoing general objects in 35 view, the invention will now be described with reference to the accompanying drawing, illustrating one form of embodiment of the invention, after which those features and combinations of parts deemed to be novel 40 will be severally set forth and defined in the appended claims.

In the drawing—

Figure 1 is a vertical longitudinal sectional view of a portion of a boiler furnace 55 fire chamber, illustrating the application of my improved water back construction.

Fig. 2 is an enlarged longitudinal sectional view of the water back construction proper;

Fig. 3 is a transverse section on the line 60 III—III, on a still larger scale; and

Fig. 4 is a similar sectional view illustrating the construction as embodied in a design differing only in form of cross-section.

Referring to the drawing in detail, this 65 illustrates the water back or water circulating member as comprising an outer tubular water casing 2, within which is centrally arranged a feed water tube 4 extending longitudinally through the casing 2 and provided 70 at its outer end with a feed water passage 6, the casing 2 having one end closed by the cap 8 and its other end provided with the outlet passage 10. The feed tube 4 may be formed with the exterior thread 12 for adjustable mounting of a series of correspondingly threaded baffle elements 14, which may be clamped in their proper spaced relation by means of lock nuts 16. These baffle elements are formed with the spacing lugs 18 80 for engagement with the interior face of the outer casing 2, said elements being arranged eccentrically within said outer casing, as illustrated in Figs. 3 and 4, with one side of each baffle element in contact with the casing, and spacing lugs 18 projecting into engagement with the casing at other points as shown. The contour of the baffle elements 85 is of an outline corresponding to the form of cross-section of the outer casing 2, being 90 represented as circular in Fig. 3, and as square in Fig. 4.

Fig. 1 illustrates the relation in which the water back or water circulating member, as thus constructed, is specially designed for 95 use, this being in connection with the overhanging portion of the bridge wall 20 of a furnace and at the point overlying the air passage 22 at the ash end of the stoker conveyor 24. This portion of the bridge wall 100 is particularly subject to the destructive action of the heat of the furnace, requiring repeated renewal, since the air passage 22, for proper combustion, must be kept always at practically the same size and not allowed 105 to admit more than just the required volume of air. The cooling action of the water passing through the water back or circulating member serves to keep down the temperature upon the flame side of the casing 110 2, as will be readily understood. In the absence of any baffle construction, however, the

friction of the relatively large surface of the outer casing walls would retard the flow of water along the latter, so that the circulation would tend to be more rapid toward the 5 interior. For the purpose, therefore, of producing a faster flow at the points where the transfer of heat is most needed, the baffle elements are provided in the number and positions required for partially obstructing 10 the flow through the interior of the apparatus, and for directing said flow chiefly along the inner face of the outer casing 2; and preferably, as shown in Figs. 1, 3, and 4, said baffle elements are arranged eccentrically 15 within said casing, since but one side of the casing is exposed directly to the fire chamber and it is hence sufficient to quicken the water flow on that side only.

It will thus be apparent that a simple and 20 efficient arrangement and construction has been devised for fulfilling the objects of the invention. A substantial increase in the rate of water flow is produced at the required points for accelerating the heat transfer 25 and preserving the parts most severely subjected to the heat, and this is done without materially decreasing the volumetric capacity of the circulating member. Moreover, since the direction of the water flow 30 along the described course, and the rate of said flow, are such as to be adapted to secure the most efficient transfer of heat at the flame side of the apparatus, it will be seen that a lesser quantity of fluid will be required for 35 the circulating medium.

While the foregoing represents what is now deemed to constitute the preferred form of embodiment of the invention, the right is reserved to such formal changes and modifications as may fairly fall within the scope 40 of the following claims.

Claims:

1. In a furnace wall construction, a water back member comprising an outer casing 45 mounted with one side thereof exposed to the flame side of the wall, a feed tube mounted longitudinally within said casing, and baffle elements mounted in the space between said casing and feed tube and arranged in 50 position to direct the flow of water in a path along the flame side of said casing.

2. In a furnace bridge wall construction, a water back member comprising an outer

casing mounted with one side thereof exposed to the flame side of the bridge wall, a feed tube mounted longitudinally within said casing, and a series of spaced baffle plates mounted at right angles to the axis of the feed tube and in the space between the latter and said casing in position to direct the flow of water in a path along the inner face of the flame side of said outer casing.

3. In a furnace bridge wall construction, a water back member comprising an outer 65 casing mounted with one side thereof exposed to the flame side of the bridge wall, a feed tube mounted longitudinally within said casing, and baffle elements mounted in the space between said casing and feed tube, 70 said baffle elements having each a contour of substantially the same form as the cross-section of said casing and arranged in position to direct the flow of water in a path along the inner face of the flame side of 75 said casing.

4. In a furnace bridge wall construction, a water back member comprising an outer casing mounted with one side thereof exposed to the flame side of the bridge wall, 80 a feed tube mounted longitudinally within said casing, and a series of spaced baffle elements mounted in the space between said casing and feed tube, said baffle elements having each a contour of substantially the 85 same form as the cross-section of said casing and carried eccentrically within the latter in position to direct the flow of water in a path along the inner face of the flame side of said outer casing. 90

5. In a furnace bridge wall construction, a water back member comprising an outer casing mounted with one side thereof exposed to the flame side of the bridge wall, a feed tube mounted longitudinally within 95 said casing, and baffle elements mounted in the space between said casing and feed tube, said elements being of a contour of the same form as the cross-section of the casing and mounted eccentrically within the latter with 100 one side of each of said elements in contact with the casing on the side opposite the flame side of the casing, whereby the flow of water is directed in a path along the inner face of the flame side of said casing. 105

FRANK A. HURLBUT.
